UNITED STATES PATENT OFFICE.

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A PLATE OR ANALOGOUS ARTICLE.

Application filed December 8, 1922. Serial No. 4,528. Term of patent 7 years.

To all whom it may concern:

Be it known that I, HAROLD E. NOCK, a citizen of the United States, residing at Newburyport, in the county of Essex and State of Massachusetts, have invented a new, original, and ornamental Design for a Plate or Analogous Article, of which the following is a specification, reference being had to the accompanying drawing, forming a part thereof.

The figure is a plan view of a conventional plate showing a section of the bor-

der embellished with my new design, it being understood that the ornamentation shown is continued around the entire periphery of the plate.

The design comprises an ornamental decoration the dominant feature of which is a representation of lace.

I claim:

The ornamental design for a plate or analogous article, substantially as shown and described.

HAROLD E. NOCK.
